WORKHOLDING DEVICE HAVING MEANS FOR ANGULAR CUTOFF

Victor Debs, Ridgewood, N.Y., assignor to American Machine & Foundry Company, a corporation of New Jersey

Filed Aug. 23, 1957, Ser. No. 679,825
6 Claims. (Cl. 259—110)

This invention relates in general to work piece holding vises and more particularly to vises that may be adjusted to secure one or more work pieces at an angle to the path of the blade of a cutoff machine.

An object of this invention is to provide an angled cutoff vise in which the fixed jaw of the vise pivots near its cutoff side so that the fixed jaw does not swing very far towards or away from the blade of a cutoff machine.

Another object of this invention is to lock in position the pivotally mounted fixed jaw of an angled cutoff vise by means of hold down nuts and slidably mounted studs which extends through straight slots in the base of the pivotally mounted fixed jaw.

A further object of this invention is to provide an angled cutoff vise wherein the movable jaw pivots to engage a work piece in any angular position in which the work piece is held by the pivotally mounted stationary jaw.

Still another object of this invention is to provide an angled cutoff vise having indexing means attached to its adjustably pivoted fixed jaw to allow the jaw to be set and locked into position in a number of pre-selected angles.

An additional object of this invention is to provide an angled cutoff vise having hold down bars secured to extend between the jaws of the vise so that the vise and the hold down bars may be used in combination as a nesting device to hold a number of work pieces.

A still further object of this invention is to provide a more versatile work piece holding vise for use in combination with a horizontal band saw machine.

Additional objects, advantages and features of invention reside in the construction, arrangement, and combination of parts involved in the embodiments of the invention and its practice otherwise as will be understood from the following description and accompanying drawings wherein:

FIG. 1 is a side elevation of the first embodiment of the angled cutoff work piece holding vise with sections broken out of its length and the remaining portions brought closer together;

FIG. 2 is a plan view of the first embodiment of the angled cutoff work piece holding vise with sections broken out of its length and the remaining portions brought closer together and with an angled position of the jaws shown in dotted lines;

FIG. 3 is a side elevation of a broken away portion of the second embodiment of the angled cutoff work piece holding vise with hold down bars mounted upon it;

FIG. 4 is a plan view of a broken away portion of the second embodiment of the angled cutoff work piece holding vise with hold down bars mounted upon it and with an angled position of the jaws shown in dotted lines;

FIG. 5 is an end elevation of the second embodiment of the angled cutoff work piece holding vise with hold down bars mounted upon it; and

FIG. 6 is a section taken on line 6—6 in FIG. 1.

2

Referring to the drawings in detail, FIG. 1 shows the elements that comprise the first embodiment of the work piece holding device. The frame 10 of the work piece holding device is secured to a horizontal band sawing machine by means of the machine screws 9 which pass through the frame flanges 11. Two way elements or members 12 are secured to the two sides of the frame 10 by means of the machine screws 8 to form a rectilinear way, running longitudinally of the holding device, between said way elements or members. The ratchet rack 13 which is T shaped in section is slidably mounted on top of and between the two way members to be held in engagement with them by means of the slide members 14 and 15 which are secured to the bottom of the ratchet rack to extend partially beneath both way members. The machine screws 7 hold the slide members to the ratchet rack.

As shown in FIG. 6, the downward projection 16 of the slide member 15 extends between the two arms 17 and 18 of the yoke 19. The two arms of the yoke are secured to the downward projection by means of the pin 20 which is driven into place in the yoke and in the downward projection through the apertures 21 in the sides of the frame 10. The pin 20 is then locked in place by means of the snap rings 22.

Referring again to FIG. 1, the yoke 19 is fixed to the operating rod 23 which may be extended or retracted by means of the hydraulic cylinder 24. The hydraulic cylinder is secured to the end member 25 of the frame 10 by means of the machine screws 6 which pass through the mounting flange 26 of the hydraulic cylinder and into the end member 25. As a hydraulic fluid is forced into the hydraulic cylinder from the tubing 27 which is attached by means of the fitting 28, the operating rod is extended to slide the ratchet rack away from the hydraulic cylinder; and, as the hydraulic fluid is allowed to flow from the hydraulic cylinder, the operating rod is withdrawn to slide the ratchet rack towards the cylinder.

As is further shown in FIG. 1 and in FIG. 2, the end of the frame 10 disposed away from the hydraulic cylinder has the jaw supporting way members 29 and 30 fixed to it by means of the counter sunk, flat head machine screws 5. The movable jaw support bracket 33 is slidably secured above and between the jaw supporting way members in much the same manner as the ratchet rack is secured to the way members 12. The slide member 34 is secured to the movable jaw support bracket by means of the machine screws 7 to contact the under surface of both the jaw supporting way members. The pawl 35 is pivotally fastened between the flanges 36 and 37 of movable jaw support bracket with the pin 38. Attached to the front of the movable jaw support bracket with the bolt 39 is the movable jaw swivel 40 which has the hinge pin 41 extending through its upper and lower horizontal flanges 42 and 43. Disposed above these flanges and about the hinge pin 41 are movable jaw support flanges 44 and 45 which are integral parts of the movable jaw 46. This hinge pin is held in place by means of the locking nuts 47. The stop member 1 is formed on the back of the movable jaw 46 to contact the arresting surfaces 2 formed on the front of the movable jaw swivel 40 so that the movable jaw cannot pivot in one direction beyond a position normal to the axis of the frame. The wear resistant facing 48 of the movable jaw is secured in position with the machine screws 4.

The fixed jaw 49, which has its wear resistant facing 50 secured in place by means of the machine screws 4, has the horizontal base plate 51 resting upon the jaw supporting way members. Two flanges 52 and 53 brace the jaw to the horizontal base plate which is pivotally secured to the jaw supporting way member 29 by the pin 54. Two elongated slots 55 and 56 extend substantially parallel to the fixed jaw 49 to have the hold down bolts 57 and 58 disposed through them to be turned into the T nuts 59 that are disposed below and between the jaw supporting way members. The frame 10 below the fixed jaw 49 contains the apertures 60 which may be entered by the set screws 61. A rod which has a stop member affixed to it may be disposed through these apertures 60 and locked in place with the set screws 61 to longitudinally position a work piece extending between the jaws. The end plate 62 may also be added to the frame 10 to further strengthen and brace it.

The first embodiment of the angled cutoff work piece holding vise may be used as follows in combination with a horizontal band saw. The blade of such a band saw would be arranged to move downwards disposed in a substantially horizontal position parallel to and slightly outside the jaw supporting way 29. The blade would be traveling from the movable jaw toward the fixed jaw along the line A—A FIG. 2 so that a work piece would tend to be forced against the fixed jaw as it was cut. If the work piece was to be cut off square, the fixed jaw would be secured as shown in FIG. 1 and FIG. 2 by tightening the hold down bolts 57 and 58. The work piece would then be placed between the jaws on the jaw supporting way members next to the face of the fixed jaw. The movable jaw could then be slid against the work piece as the movable jaw support bracket is free to slide along the jaw supporting way members as the pawl rides over the teeth of the stationary ratchet rack. As the hydraulic cylinder is activated to slide the rack towards the stationary jaw, the teeth of the ratchet rack engage the pawl to slide the movable jaw towards the fixed jaw and secure the work piece between them.

If a work piece is to be cut at an angle, the hold down bolts 57 and 58 would be loosened and the indexing pin 63 withdrawn from its aperture in the base plate of the fixed jaw and a corresponding aperture 67 in the jaw supporting way member 30. Then the fixed jaw could be pivoted about the pin 54 as the degree of pivot is indicated by the markings 68 on the top surface of the jaw supporting way 30. It should be noted that the fixed jaw in any angular position remains close to the cutter line indicated at A—A FIG. 2. The angle of cut may also be set using the indexing pin 63 which is fastened to the fixed jaw by the screw 64 and the line 65 to be dropped into an aperture 66 when this aperture is properly aligned with the aperture in the base plate of the pivoted fixed jaw. After the hold down bolts are tightened to hold the fixed jaw at the desired angle, the work piece is placed between the jaws as has been described except that the work piece is now arranged parallel to the pivoted face of the fixed jaw. As the movable jaw is activated to grip the work piece, it pivots about the hinge pin 41 to align itself with the work piece and force it against the fixed jaw. The dotted line drawings of the jaws in FIG. 2 show the relative positions of the jaws to hold a work piece for a 30 degree cut. The aperture 66 is shown formed in the jaw supporting way member 30 so that, when the indexing pin passes through the horizontal base plate and the aperture 66, the fixed jaw will be pivoted 30 degrees. Further apertures could be formed in the jaw supporting way member 30 so that different degree settings of the fixed jaw could rapidly be made using the indexing pin.

The particular construction of this embodiment of the invention enjoys many advantages. For example, the fixed jaw is adjustably pivoted about the pin 54 which is placed near the path of the saw blade so that the edge of the fixed jaw disposed towards the blade cannot pivot very

far in relation to the blade. This feature insures that the work piece will be backed up by the fixed jaw close to the actual cut regardless of the angle of cut. Also, the hold down bolts are disposed through straight slots in the horizontal base plate 51. Straight slots are both stronger and easier to form than curved slots; however, these straight slots are able to allow the base plate to pivot about the pin 54 because the hold down bolts extend into the slidably mounted T nuts which ride below and within the jaw supporting ways. Naturally the slot disposed furthest from the pin 54 must be longer and it will urge the hold down bolt disposed within it to slide further as the fixed jaw is pivoted. In addition the swivel construction of the movable jaw allows a great saving in time as only one jaw need be set to make an angled cut. Finally the large stud 69 and the two smaller studs 70 that extend upwards, respectively, from the top of the movable jaw and the top of the fixed jaw, enable the nesting device, that is the subject of my co-pending application entitled Workholding Device which was filed August 16, 1957, to be secured to the angled cut-off vise. This enables the first embodiment of the invention to be used as a nesting device and thereby greatly increases its versatility.

The elements comprising the second embodiment of this invention correspond in general to the same elements comprising the first embodiment with the following modifications and additions. Referring to FIG. 5, in the second embodiment of the invention, the jaw supporting way members 29 and 30 are shown formed as integral parts of the frame 10. As shown in FIGS. 3 and 4, the movable jaw support bracket 33 is provided with an upward extension 71 to hold the stud 69 provided for the purpose of securing one end of member 74. In addition, the vertical supports 72 and 73 are fixed to the jaw supporting way members with the bolts 3 to support the two studs 70, which support the other end of member 74. These vertical supports are disposed so as to be behind and clear of the adjustable pivotal travel of the fixed jaw.

Referring now to FIG. 4, this nesting device consists of a main support member 74 fixed to the upper ends of the vertical supports 72 and 73 by the nuts 75 which are turned down about the studs 70. The other end of the main support member is slidably secured to the top surface of the upward extension 71 of the movable jaw support bracket by the stud 69 which extends through the longitudinal slot 76. The nut 77 and the washer 78 hold the main support member down in sliding contact with the upward extension 71 as the movable jaw is opened and closed. The hydraulic cylinder 79 is slidably secured to main support member by means of the bolts 80 which secure the lower flange 81 of the hydraulic cylinder 79 to the T nuts 82 through the slot 76. The upper flange 83 of the hydraulic cylinder 79 is secured to the lower flange 81 by means of the bolts 84. The cross member 85 is fixed to the piston of the hydraulic cylinder 79 by means of a threaded securing member 96 which is cooperatively engaged with a threaded recess in the piston. The threaded securing member is rigidly fixed to the cross member 85 by the bolt 104. An upward projection 86 of the piston extends into an aperture in the upper flange of the hydraulic cylinder 79 so that the upward projection and the entire piston may be turned within the hydraulic cylinder by turning the easily reached slot 87. This turning may extend the threaded securing member and lower the cross member 85. The details of the construction of this hydraulic cylinder are shown in my fore-mentioned pending application. Hydraulic fluid under pressure is introduced through the tubing 88 and the fitting 89 to activate the cylinder and lower the cross member.

As shown in FIG. 3 and FIG. 4, the hold down bars 90 and 91 are secured to the end portions of the cross member by the bolts 94 which extend through the longitudinal slots 95 in the hold down bars. These hold down bars may be protected by suitable wear resistant linings 97 and 98. FIG. 5 further shows the two vertical walls

99 and 100 formed on the cross member 85 to have the stops 101 and 102 secured to their top surfaces with the screws 103.

This second embodiment of the invention may be used as follows. If a number of work pieces are to be secured for a simultaneous cutoff operation, they would be stacked on the jaw supporting way members between the jaws which would be secured normal to the axis of the frame 10 as shown in FIG. 3 or FIG. 4. The bolts 80 and the bolts 94 would be loosened so that the hydraulic cylinder could be slid into a position midway between the jaws as the hold down bars are adjusted to at least extend between the jaws whereupon the bolts 80 and the bolts 94 would be tightened. At this time the hold down bars 90 and 91 can be brought into light contact with the work pieces by turning the slot 87 to lower the cross member 85. If a hydraulic fluid is introduced under pressure through the tubing 88 into the hydraulic cylinder 79, the piston is forced downwards to carry the cross member and the hold down bars downwards. Therefore, as the hydraulic cylinders 79 and 24 are simultaneously activated, the pawl moves the jaws together as the hold down bars move downward to clamp the work pieces between the jaws at the same time as they are clamped between the jaw supporting ways and the hold down bars. The work pieces are thus secured for a simultaneous square cutoff operation.

If a number of work pieces are to be secured for a simultaneous angled cutoff operation, the fixed jaw is pivoted and locked into position as has been described for the first embodiment of the invention. The dotted line drawing of the jaws in FIG. 4 shows the jaws pivoted in position to hold a number of work pieces in alignment for a 30 degree cut off operation. The hydraulic cylinder 79 is then slid into a position midway between the pivoted jaws as the hold down bars are adjusted to extend beyond the ends of the jaws. Both hydraulic cylinders are activated to secure the work pieces between the swiveled jaws and between the hold down bars and the jaw supporting way members for an angled cutoff operation.

It can readily be seen that there are many advantages inherent in the particular construction of this second embodiment of the invention. The hold down bar 90 on the cutoff side of the vise clears the cutoff side of both jaws so that it does not interfere with their angular adjustment. Also, since the main support member is not secured to the swiveling portions of either jaw, it remains independent of the angular adjustment of the jaws. Because the downward force exerted upon the hold down bars can be centered approximately between the jaws, this combination can much more effectively secure the work pieces. This angled cutoff vise with hold down bars results in one of the most versatile work piece holding mechanisms ever adapted to be used in conjunction with cutoff machines.

While I have disclosed my invention with particularity in the best forms known to me, it will nevertheless be understood that these are purely exemplary and that modifications in the construction, arrangement, and combination of parts, substitution of materials and substitution of equivalents mechanically and otherwise, may be made without departing from the spirit of the invention, except as it may be more particularly limited in the appended claims wherein I claim:

1. In a work holding vise for use with a cutoff saw or the like, the combination of frame means having a supporting surface of substantial width and having a side adapted to be disposed closely adjacent and parallel to the cutting line of the saw or the like; a pair of jaw structures mounted on said frame means and spaced in a direction generally parallel to said side of said frame means and extending upwardly from said surface; and means operatively arranged to effect relative rectilinear movement of said jaw structures toward each other in

said direction; one of said jaw structures comprising a jaw member having a flat, vertically disposed work-engaging face of substantial width extending transversely relative to said direction and having an end disposed adjacent said side of said supporting surface, means pivotally mounting said jaw member on said frame adjacent to said side for pivotal movement of said jaw member about a vertical axis located closely adjacent to said end, and means, spaced from said pivotally mounting means, operative to lock said jaw member in pivotally adjusted position at any of a number of selectable angles with respect to said side; the other of said jaw structures comprising a jaw member having a work-engaging face directed toward said one jaw structure, and means mounting said last-mentioned jaw member for pivotal movement about a vertical axis.

2. A workholding device in accordance with claim 1 having power means operatively connected to said other jaw structure to apply force thereto to move said other jaw structure toward said one jaw structure, said vertical axis being substantially centered with respect to the line along which force is applied to said other jaw structure by said power means.

3. A workholding device in accordance with claim 1 having a first and a second rigid support member extending upward from said surface, an elongated horizontal frame member mounted on said supports, power means mounted on said horizontal frame member, a horizontal hold down member connected to said power means and vertically displaceable by said power means, said jaw members and said hold down member disposed so as to permit the cooperative clamping of one or more work-pieces therebetween at any of said angles.

4. In a work holding vise for use with a cutoff saw or the like, the combination of a horizontal base having a substantial width and having a side adapted to be disposed closely adjacent and parallel to the cutting line of the saw or the like; a slide; means carried by said base and forming a way extending parallel to said side of said base and spaced therefrom, said slide being mounted for rectilinear movement along said way; power means connected to said slide and arranged to apply an actuating force thereto to move the slide along said way; a first jaw member extending transversely of said way and mounted on said slide for pivotal movement about a vertical first axis located in mid-position laterally on said base; a relatively fixed jaw structure comprising a horizontal base plate, said plate having substantial width, a vertically disposed elongated second jaw member rigidly connected to said base plate and extending transversely of said way, said second jaw member having an edge disposed closely adjacent to said side of said base, said base plate elongately perforated in mid-lateral position thereof transversely of said way; pivot means mounting said jaw structure on said base for pivotal movement about a second vertical axis located closely adjacent said side of said base, said second axis displaced substantially laterally from said first axis, said pivot means affording rigid support for said jaw structure in directions normal to said second axis; a jaw structure hold down member, separate from said pivot means, disposed to move along said way parallel to said side and located below the base plate of said jaw structure, said member being restrained against movement in other directions, and rigid fastener means extending downwardly through said perforation and operatively associated with said member to clamp said jaw structure in pivotally adjusted position to said base.

5. As a subcombination of a vise, a rotatable elongated jaw having an operating uniplanar face and a first and a second means for securing said jaw against displacement when engaging a work piece, said first means being a pin disposed near one end of said jaw to minimize vibration caused by the operation of a tool near said end, said pin serving also as the axis about which said jaw is rotatable, said second means being hold down means for said jaw, displaced substantially from said pin,

and located centrally in said jaw, said hold down means comprising a base supporting said jaw, said base having spaced elements forming a straight open way, an instrumentality slidably rectilinearly in said way and restrained from other motion, said jaw perforated to form an elongated aperture parallel to said face in the central portion of said jaw, said aperture and said instrumentality disposable in said vise so as to maintain registry as said jaw is rotated, and means, interconnecting said instrumentality through said aperture to said jaw.

6. A vise having a first and a second opposed uniplanar operating face in a first and a second elongated jaw, respectively, each of said jaws rotatably adjustable in said vise and disposed to hold a work piece at a selectable angle in said vise, said first jaw perforated to form an elongated aperture in its central portion parallel to its said respective face, first securing means in said vise for said first jaw, said first securing means displaceable rectilinearly and restrained from other motion in said vise and disposed to maintain registry with said aperture as said first jaw is rotated, said first securing means disposed to provide a substantially centrally located stabilizing means for said first jaw, when said first jaw is rotated into any selected angular position, a second securing means in said vise for said first jaw, spaced substantially from said first securing means, and closely adjacent an end of said first jaw, said end closely adjacent the position of a tool operable on said work piece near said end, said second securing means disposed to minimize vibration of said work piece due to the action of said tool, said second securing means forming also the axis about which said

5

first jaw is rotatable, and a third securing means in said vise for said first jaw, said third securing means being near the opposite end of said jaw from said axis, said third securing means being a displaceable pin in registry with means for indicating the angle of rotation of said first jaw in said vise.
